UNITED STATES PATENT OFFICE

EDWIN D. ROSS, OF DETROIT, MICHIGAN

WINDOW

Application filed August 20, 1928. Serial No. 300,620.

This invention relates to improvements in windows, and refers more particularly to windows wherein slides having sashes mounted on them are adapted to be moved vertically in stile grooves.

It is an object of the invention, among other things, to provide a window wherein the sash is pivotally mounted on its slides and is adapted to be moved about a horizontal axis, and swung inwards to a slight extent for purposes of ventilation at any vertical position of the slides in their stile grooves.

Another object of the invention is to provide a window wherein the sash is adapted to be swung inwards into a substantially horizontal position when it and its slides have been raised to a predetermined position, and wherein means are provided for locking the slides against vertical movement in their stile grooves as long as the sash remains in its substantially vertical position.

With these and other objects and advantages in view, which will become apparent as the specification proceeds, an embodiment of the invention is hereinafter more fully described with the aid of the accompanying drawings, in which:

Figure 1 illustrates a side elevation looking onto a plate pivotally mounted on one slide to which plate one side of a sash is adapted to be secured; the position of the sash when in partly open position is also indicated.

Figure 2 is a front elevation of part of a sash showing parts of the frame and correlated portions in section.

Figures 3 and 4 are enlarged sections on the lines 3—3 and 4—4 respectively.

Figure 5 is an enlarged detail.

Figure 6 shows a side view, partly in section, of a sash plate in its substantially horizontal position and the correlated parts.

Figure 7 is an enlarged detail of the slide, and catch in the stile groove.

Figure 8 is a section on the line 8—8 of Figure 7 and is continued downwards to illustrate the pivotal mounting of the sash and sash plate.

Figure 9 is an enlarged sectional view of the dog retracting mechanism, and

Figure 10 depicts an enlarged view of the engaging member.

Referring to the drawings, 1 designates a window having stile grooves 2 in which slides 3 are adapted to move vertically. The slides 55 consist of substantially channel shaped members having their open sides outwardly disposed, and inwardly directed flanges 4 along their rear margins forming receiving grooves 5 open from the front. Lengthwise of the 60 sides of a sash 6 sash plates 7 are secured. The rear margins 8 of the plates 7 are spaced from the sides of the sash and are adapted to engage the grooves 5 thereby functioning as weather stripping; and intermediately of the 65 length of one of these sash plates a portion of its rear margin is cut away so that that portion of that plate, when parallel with its slide, terminates flush with the front edge of 70 the adjacent flange 4.

The inner side of one of the sash plates 7 is provided with a longitudinal groove 9 to receive a portion of a sliding member 10 to which an extension arm 11 is pivotally attached. The opposite end of this extension arm is pivotally fastened to one end of an arm 12, and the opposite end of the latter is pivotally attached to the slide 3. The arm 12 and its extension 11 are so positioned that when the sash is in vertical position they lie 75 in one of the receiving grooves 5 and opposite the sash plate portion 7 the rear margin of which is cut away. Hinge pins 13 extend through the lower ends of the slides 3, sash plates 7, and take into the sides of the sash 80 6. These pins 13 may be held in position as by springs 14.

Pivottally mounted within the channel-shaped portion of one of the slides 3 is an arm 15 normally held forwardly by a spring 90 16; through this arm is a locking pin 17 which projects through a slot 18 in the slide 3 and is adapted to be engaged by a recess 19 in the rear edge of one of the plates 7 when the sash is in vertical position. On the central face 95 of one of the stile grooves 2 is a catch 20 having a receiving slot 21 therein. When the sash is swung inwardly so that the pin 17 is released from the recess 19 and may be moved forwardly by the spring 16 the pin engages 100

the slot 21 provided the sash and its slides have been raised to such a height that the pin and slot come into engagement. When this occurs the sash and slides are held against vertical movement in their stile grooves. Other means for holding the sash and slides against vertical movement when the former is moved pivotally may be employed when desired.

10 Secured to the outer side of one of the slides 3 is a flat spring 22 having an opening 23 therethrough towards its free end, and opposite the opening 23 an aperture 24 is provided through the central portion of the slide.

15 A dog 25 passes through the opening 23 in the spring 22 and is so held thereby that its inner end normally projects through the slide aperture 24. On the outer end of the dog 25 is a transverse portion 26 which is spaced 20 outwardly from the said spring 22. On the central face of one of the stile grooves 2 an engaging member 27 is arranged which is adapted to engage the inner sides of the transverse portion 26 of the dog 25 and draw the latter outwardly as the sash is moved vertically in its stile grooves so that at one position of the slides and sash the dog is brought outwardly substantially flush with the inner side of its slide. Incidentally this should occur when the locking pin 17 is opposite its slot 21, so that the slides and sash are locked against vertical movement at the time the dog is withdrawn; for obviously when the latter occurs the arm 12 is free to swing into 35 the position shown in Figure 6. 28 denotes a conventional type of fastener for holding the upper sides of the sash in engagement with the slides.

From the foregoing it will be seen that, at any vertical position of the slides and sash the latter may be moved pivotally to the limit of movement permitted by the arm extension 40 11, as indicated in Figure 1. When the slides and sash have, however, been raised to such 45 position that the engaging member 27 retracts the dog 25, the arm 12 is then also free to swing so that the sash may be brought into a substantially horizontal position as indicated in Figure 6.

50 While in the above description the preferred construction has been described, it is understood that the invention is subject to such alterations and modifications as fall within the scope of the appended claims.

55 What I claim as my invention and desire to secure by Letters Patent is:

1. In a window, the combination of a frame having stile grooves therein, slides vertically movable in said grooves, a sash pivotally mounted between said slides, an arm pivotal on one of said slides, an extension arm pivotally secured at one end of said arm and having its opposite end in slidable engagement with one side of said sash, means adapted to 60 retain said arm substantially in alignment

with its slide and said extension arm being adapted to swing and permit limited pivotal movement of the sash.

2. In a window, the combination as described in claim 1 wherein means are provided for retracting the dog when the sash reaches a predetermined position in its frame so that the arm may swing pivotally as well as the extension arm and allow the sash to assume a substantially vertical position. 70

3. In a window, the combination of a frame having stile grooves therein, slides vertically movable in said grooves, a sash pivotal between said slides, an arm pivotally mounted on one of said slides, an extension arm pivotally secured at one end to said arm and having its opposite end in slidable engagement with one side of said slide, a dog adapted to retain said arm substantially in alignment with its slide, said extension arm being adapted to swing and permit limited pivotal movement of said sash, means for retracting said dog and allowing said arm also to swing pivotally when said sash and slides reach a predetermined position in the stile grooves, and means for holding said slides against vertical movement when said sash is swung pivotally beyond a certain extent. 80

4. In a window, the combination of a frame having stile grooves therein, slides vertically movable in said stile grooves, a sash pivotal between said slides, an arm pivotal on one of said slides, an extension arm having one end pivotally secured to said arm, a sliding member pivotal on the other end of said extension arm, sash plates on the sides of said sash, a longitudinal groove formed in one of said sash plates for said sliding member to travel along, and a dog adapted to hold said arm normally against pivotal movement and to permit said extension arm and said sash to move pivotally a limited extent. 90

5. In a window, the combination of a frame having stile grooves therein, slides vertically movable in said stile grooves, a sash pivotal between said slides, an arm pivotal at one end on one of said slides and having its opposite end connected to said sash, a dog adapted to engage said arm and hold it against pivotal movement, an engaging member on said stile groove adapted to withdraw said dog as said slides are brought to a predetermined position thereby permitting pivotal movement of said arm and allowing said sash to swing, and means for returning said dog to its arm engaging position as it is moved out of engagement from said engaging member. 110

6. In a window, the combination of a frame having stile grooves therein, slides vertically movable in said stile grooves, a sash pivotal between said slides, receiving grooves formed in the inner sides of said slides accessible from the front, sash plates on the sides of said sashes having their rear margins spaced from said sashes and adapted to engage said 120 130

grooves, one of said rear margins being cut away intermediately of its length, an arm pivotally mounted on said slide, an extension arm pivotal on said arm, said arm and said extension arm being adapted to nest in the receiving groove portion opposite which the rear margin of the sash plate has been cut away, and the extension arm being slidably connected to one side of said sash.
